William
Chenot
No 178

Design for Boxes
Fig. 1.

Patented May 2 1848.

Fig. 2.

An improved design for a writing-table
by William Chenot.

UNITED STATES PATENT OFFICE.

WILLIAM ABENDROTH, OF PORT CHESTER, NEW YORK.

DESIGN FOR A COOKING-STOVE.

Specification forming part of Design No. 178, dated May 9, 1848.

To all whom it may concern:

Be it known that I, WILLIAM ABENDROTH, of Port Chester, county of Westchester, and State of New York, have invented or produced a new and Improved Design for a Cooking-Stove; and I do hereby declare that the following is a full and exact description of the same, reference being had to the annexed drawings, which make a part of this specification.

My design is in the style of art denominated "Grecian." The edges or sides have an architrave with moldings. The upper parts of the architrave have knees similar to the ordinary Grecian architrave of doorways. The facies of the architrave are ornamented with scrolls and foliage rising out of vases, with birds and butterflies. The front view, Figure 1, shows the space between the architrave embellished with molded panels for lettering cast upon them, with openings of talc or similar transparent material, the parts between them

being ornamented with foliage branching out of vases. The feeder projects slopingly with talc openings in the doorway. The top plate of the stove is curved over the center of the feeder. Fig. 2 is a side view. The parts between the architrave consist of a small square panel and a paneled door. The panels are embellished with scrolls and foliage. The architrave is ornamented with embellishments similar to those on the front view. The top plate is finished around its edge with an egg-molding.

What I claim as my design, and desire to secure by Letters Patent, is—

The herein-specified pattern for a cooking-stove, composed of architraves, panels, moldings, and ornamental parts, as set forth.

WM. ABENDROTH.
